NAIL-TRANSFERRING MECHANISM

William S. Dallas, Beverly, Mass., assignor to
United Shoe Machinery Corporation, Borough
of Flemington, N. J., a corporation of New
Jersey

Application July 18, 1940, Serial No. 346,169

8 Claims.

(Cl. 1—32)

My invention relates to mechanism by which nails may be received in groups or loads for delivery to inserting mechanism, it being of particular utility in connection with the transfer of such loads of nails to the die of a heel-attaching machine.

In nail-loading or transferring mechanism, the nails are commonly carried in passages formed in a member movable between nail-receiving and nail-delivering positions, they being supported upon a retaining member or gate, with which is associated a spring tending to urge it away from its nail-retaining relation. A latch engages the gate to temporarily hold it across the passages for the retention of the nails. A well-known arrangement for freeing the gate to effect nail-delivery, is to bring said gate, as the nail-holding member reaches its delivering position, into engagement with a relatively fixed member. This bends the gate, which is of thin metal, away from a latching pin fast upon the loading member, leaving the spring free to act. This may be objectionable, because, as the gate leaves the pin, it sharply assumes its normal flat condition from which it was bent for release. This movement is imparted to the nails, tending to snap them out of the loader-passages. Further, it is not always easy to so locate the fixed releasing means that it will not interfere with associated movable elements of the machine. According to another arrangement, the latching means for the gate is carried by a handle through which the operator shifts the loading member, the gate being released by movement of the handle and latch upon the loading member, when the delivery-point is reached. It is found that some operators move the loading member so abruptly that the gate will be tripped prematurely. Then too, if the loading member is power-driven, this last gate-releasing means is not available. It is an object of my invention to bring about the release of the nails by means which is independent of the manner of loader-actuation, which ensures proper delivery and which is free from interference.

In the attainment of this object, I combine with a nail-transferring member or movable loader-arm and its nail-retaining member or gate, a movable latch for the gate, and a member, preferably in the form of a lever, fulcrumed upon the transferring member in engagement with the latch and movable by contact with a relatively fixed member to release the retaining member. As herein illustrated, the latch is furnished by a pin engaged by the lever, which also has such means, as a screw, arranged for contact with the frame of the machine, which will move the lever and pin to release the gate and which may be adjusted to vary the time of such release. This organization operates positively

without nail-displacing distortion of the gate, and equally well for manual or power-operation. The latch-lever may readily be so formed and mounted upon the loader, and its point of contact with the machine-frame or other stationary element so located, that it is clear of all other associated parts. The latch-lever is most conveniently made a portion of a compound controlling unit, separably mounted upon the loading member. It is to this end fulcrumed upon a bracket secured to said loading member, the bracket also carrying a stop which limits the nail-delivering movement of the loading member, together with a cam through which may be operated a member controlling its supply of nails.

An illustrative embodiment of the invention appears in the accompanying drawing, in which

Fig. 1 is a top plan view of my improved transferring mechanism, while

Fig. 2 is a side elevation thereof, with certain associated parts omitted.

Pivoted at 10 for horizontal movement upon the frame 12 of the machine, which may be for the nailing of heels upon shoes, such as is made the subject of Letters Patent of the United States No. 1,157,688, Glidden, October 26, 1915, is a loader-arm 14. At its forward extremity the arm carries a loader-block 16, in which are vertical nail-holding passages 18 arranged in accordance with a particular inserting design. The loader-arm may be moved either directly by the operator through a handle 20, or under the power of the machine by way of a link 22 pivoted to the arm. This oscillation of the arm shifts the loader-block between a position at which it may receive loads of nails from an unillustrated distributor or supplied by hand, to one over the die-block 24 of the heeler. In the latter position, the nail-passages 18 register with passages 26 in the die-block. Pivoted upon the loader-arm is a gate or shutter 30, which may be of sheet-metal and which at its outer extremity is enlarged horizontally. As the gate is turned upon its pivot, this enlargement may be caused to lie below the block-passages 18. These passages are thereby closed, so nails supplied to the block may be retained temporarily. A spring 32, extending between the pivoted end of the loader-arm and the outer portion of the gate, exerts its force to urge said gate clear of the block-passages to permit discharge of the nails. This movement of the gate is prevented, except when the passages 18 are in registration with the die-passages 26, by the latch now to be described.

Attached to the arm 14, at 34, 36, is a bracket 38, having an upwardly projecting portion 38. Pivoted at 40 upon this bracket-portion for vertical oscillation is a bell-crank-lever 42, provided with a generally horizontal arm 44 extending

outwardly along the loader-arm and with a generally vertical downwardly extending arm 46. The arm 44 of the lever is forked at 47 to embrace a reduced portion of the head 48 of a latch-pin 50. This latch-pin passes through a vertical opening 52 in the loader-arm 14, being held against downward displacement by a flange 54 formed about it. When the gate 30 is in its nail-retaining relation beneath the loader-block 16, the pin lies within an opening 56 in said gate, holding this against the force of the spring 32. When, however, the loader-arm swings over the die-block 24 to make the delivery of tails there-to, a screw 58, threaded horizontally through the arm 46 of the lever 42, engages some relatively fixed element of the machine, as a vertical surface x upon the frame 12 at the rear of the die-block. This lifts the pin 50 from the opening 56, freeing the gate for retraction by its spring, so the nails fall from the loader-block-passages into the die-block-passages, without any upward force tending to displace them. Upon reverse movement of the loader-arm, the gate is returned to nail-retaining relation by engagement with the usual fixed contact member 59, the pin 50 being carried by its weight and the excess weight of the horizontal lever-arm 44 into the gate-opening 56. The extent of projection of the screw 58 may be varied, to cause the time of release of the nails from the loader-block to agree with the registration of the loader-block-passages with those in the die-block.

The bracket 36 also preferably serves as a support for a screw 60, threaded horizontally through the upper bracket-portion 38. This, by its contact with the frame-surface x , determines the registration of the loader-block-passages with the die-block-passages. Further, there may be secured to the upper extremity of the bracket-portion 38 a cam 62, which, by engagement with a vertical rod 64, will cause the delivery of nails from a distributor, if such a mechanism may be employed. A tripping mechanism of this character is disclosed in Letters Patent of the United States No. 1,984,109, Balcom, December 11, 1934. A slot-and-screw connection 66 allows the cam to be adjusted upon the bracket to alter its timing. All the bracket-borne elements are conveniently mounted together above the loader-arm for removal or replacement, entirely clear of unrelated elements of the machine.

Having thus described my invention, what I claim as new and desire to secure by Letters Patent of the United States is:

1. The combination with a nail-transferring member, of a nail-retaining member movable upon the transferring member, a movable latch for the retaining member, and a member pivoted upon the transferring member in engagement with the latch and movable by contact with a relatively fixed element to release the retaining member.

2. In a nailing machine, a movable loader-arm provided with nail-holding passages, a nail-retaining gate co-operating with the passages, means for urging the gate from its nail-retaining relation, a movable latch for holding the gate in its nail-retaining relation, and a lever fulcrumed upon the arm for engagement with the latch and movable by contact with a relatively fixed portion of the machine to actuate said latch.

3. In a nailing machine, a frame, a loader-arm provided with nail-passages and movable upon the frame between nail-receiving and nail-delivering positions, a gate co-operating with the passages, a spring urging the gate from its nail-retaining relation, a lever fulcrumed upon the arm, and a latch-pin for the gate engaged by the lever, the lever being movable by contact with the frame to free the gate from the latch-pin.

4. In a nailing machine, a frame, a loader-arm provided with nail-passages and movable upon the frame between nail-receiving and nail-delivering positions, a gate co-operating with the passages, a spring urging the gate from its nail-retaining relation, a lever fulcrumed upon the arm, a latch-pin for the gate engaged by the lever, the lever being movable by contact with the frame to free the gate from the latch-pin, and means arranged to vary the time of release of the gate.

5. In a nailing machine, a frame, a loader-arm provided with nail-passages and pivoted to oscillate upon the frame between nail-receiving and nail-delivering positions, a gate co-operating with the passages, a spring urging the gate from its nail-retaining relation, a lever fulcrumed upon the arm and having generally horizontal and generally vertical arms, a latch-pin for the gate engaged by the horizontal arm of the lever, and a screw threaded through the vertical lever-arm and movable in the oscillation of the loader-arm into contact with the frame.

6. In a nailing machine, a frame, a loader-arm provided with nail-passages and movable upon the frame between nail-receiving and nail-delivering positions, a gate co-operating with the passages, a latch for the gate, a bracket separably secured to the loader-arm, a latch-actuating member movable upon the bracket, an adjustable contact member carried by the actuating member and arranged to move said actuating member by engagement with the frame, and an adjustable stop member carried by the bracket for contact with the frame.

7. In a nailing machine, a frame, a loader-arm provided with nail-passages and movable upon the frame between nail-receiving and nail-delivering positions, a gate co-operating with the passages, a latch for the gate, a bracket separably secured to the loader-arm, a latch-actuating member movable upon the bracket, an adjustable contact member carried by the actuating member and arranged to move said actuating member by engagement with the frame, an adjustable stop member carried by the bracket for contact with the frame, and a nail-controlling member mounted upon the bracket.

8. In a nailing machine, a frame, a loader-arm provided with nail-passages and pivoted to oscillate upon the frame between nail-receiving and nail-delivering positions, a gate co-operating with the passages, a latch for the gate, a bracket separably secured to the loader-arm, a lever fulcrumed upon the bracket and by an arm of which the latch is carried, a screw threaded through the lever for contact with the frame, and a screw threaded through the bracket for contact with the frame, both screws being carried into contact with the frame by the oscillation of the loader-arm.

WILLIAM S. DALLAS.
